UNITED STATES PATENT OFFICE.

DANIEL BEST, OF SAN LEANDRO, CALIFORNIA.

DESIGN FOR AN ENGINE-FRAME.

SPECIFICATION forming part of Design No. 21,545, dated May 17, 1892.

Application filed April 13, 1892. Serial No. 428,053. Term of patent 14 years.

To all whom it may concern:

Be it known that I, DANIEL BEST, a citizen of the United States, residing at San Leandro, Alameda county, State of California, have 5 invented an Improvement in Designs for Engine-Frames; and I hereby declare the following to be a full, clear, and exact description of the same.

My invention consists of a novel design 10 especially adapted for the frame and bed-piece of gas-engines.

Referring to the accompanying drawings for a more complete explanation of my invention, Figure 1 is a side elevation of my frame. 15 Fig. 2 is a rear view of the same.

The leading feature of my design is the peculiar outline of the frame upon which the cylinder rests, the two merging into each other, the frame having a peculiar trough 20 shape extending from the cylinder to the end, where the crank-shaft is supported, together with downwardly-projecting legs or supports at each end and an arched under body.

A is that portion of the frame which forms 25 the cylinder, the rear end being at right angles with the axis of the cylinder. The front end of the cylinder forms an arched rib, which curves downwardly into the sides, as shown at B, forming flanges C, which extend 30 approximately in horizontal parallel lines to

the point D, where they are depressed, forming semicircular channels, beyond which they extend a short distance, as shown at E. From this point a reverse-curved rib F extends downwardly, having a foot adapted to rest 35 upon the floor. A similarly-curved rib G extends downwardly from a point beneath the cylinder, forming a corresponding foot at that end of the frame. From the interior of these feet the frame-work is curved upwardly in an 40 irregular arch, having a projecting rib around its periphery, the form of this curve somewhat resembling the shape of half a guitar, as shown at II.

The side ribs C upon the top of the frame, 45 are united by a concave trough extending from the cylinder to the opposite end of the frame and partaking approximately of the form of the interior arch II of the frame.

Having thus described my invention, what 50 I claim as new, and desire to protect by Letters Patent, is—

The design for an engine bed and cylinder, substantially as herein described and shown.

In witness whereof I have hereunto set my 55 hand.

DANIEL BEST.
